UNITED STATES PATENT OFFICE.

JOHN HOFFER, OF FAIRMONT, WEST VIRGINIA.

SAFETY-STOP FOR ELEVATORS.

1,072,008.

Specification of Letters Patent.

Patented Sept. 2, 1913.

Application filed August 8, 1912. Serial No. 714,114.

To all whom it may concern:

Be it known that I, JOHN HOFFER, residing at Fairmont, in the county of Marion and State of West Virginia, a citizen of 5 Austria-Hungary, have invented or discovered certain new and useful Improvements in Safety-Stops for Elevators, of which improvements the following is a specification.

My invention relates to the construction 10 of elevators provided with safety devices consisting of cams adapted to engage the elevator guide rails and thereby arrest the descent of the elevator upon the breaking of the sustaining cable.

15 The object of my invention is to provide a means for operating such safety devices which will be certain and effective under all conditions of service, the elevator at the same time being securely sustained throughout its normal operation.

20 A further object of my invention is to so coordinate the action of such safety devices, when used on freight or mine shaft elevators sustained in pairs by a single cable, 25 and movable in opposite directions, that the safety cams of each elevator will, through a single instrumentality, become effective simultaneously.

25 My invention is illustrated in the accompanying drawings, which form part of my specification, and in which—

Figure 1 is a front elevation of a passenger elevator; Fig. 2 is a side elevation of the elevator shewn in Fig. 1; Fig. 3 is an enlarged plan view of Fig. 1, showing in detail the construction of the safety device; Fig. 4 is a sectional view taken on the line IV—IV Fig. 3; Fig. 5 is a sectional view taken on the line V—V, Fig. 3; and Fig. 6 is an elevation of a pair of freight or mine shaft elevators embodying certain features of my invention.

In the several figures like numerals are used to designate like parts.

45 Referring particularly to Figs. 1 to 5 of the drawings, the elevator car 1 is suitably arranged to move between guides 2, and is sustained by a supporting cable 3, which passes over a sheave 4, mounted in suitable 50 framework 5 at the top of the elevator shaft.

As heretofore constructed such elevator cars have been provided with safety-cam stopping devices, which have been brought into operation upon the breaking of the sustaining cable by springs or by weights. The spring-operated safety cams are uncertain

in their action for the reason that the springs frequently become set and fail to operate in the case of an emergency. On the other hand no structurally efficient means 60 has as yet been provided for using weights to bring the safety-cams into engagement with the guide, the elevator car at the same time being securely and properly sustained throughout its normal operation. 65

In the elevator shown herein, two shafts 6 are rotatably mounted in the upper portion of the car 1, and to each end of each shaft a toothed cam or eccentric 7 is rigidly secured. To each shaft 6 I also secure two 70 arms 8, such arms preferably being placed near the ends of the shafts and extending toward the center of the car. A pair of levers 9 are pivoted in suitable supports 10 secured to the cross beam 11 of the car, and between such supports I secure straps 12 adapted to extend over the inner ends of said levers, as shown. The outer ends of the levers 9 are slotted in order to receive the arms 8 which extend through such slots. 75 At the outer end of each lever 9 a rope or cable 13 is attached, each rope extending over sheaves 14 and 15, and having a weight 16 secured to its other end.

In the operation of this elevator, the 85 weight of the car is normally carried by the cable 3, which holds the levers 9 in their bearing positions upon the straps 12. When the cable 3 breaks, or for some other reason becomes slack, the weights 16, through 90 the ropes 13, reverse the normal positions of the pivoted levers 9, and in this reverse movement the levers cause the arms 8 of the cam shafts to be raised and thereby bring the cams 7 into engagement with the 95 guides 2. It will be seen that, in this particular arrangement, a very positive and quick action of the safety cams is assured in case of accident to the supporting cable. Furthermore, it will be seen that, during 100 the normal operation of the elevator, the car will be provided with a structurally adequate support.

My invention has to do also with a particular arrangement of safety cam operating devices when used on freight or mine shaft elevators, the cars of which are sustained in pairs by a common cable, and which move in opposite directions with relation to each other through their respective shafts. As usually constructed, each elevator car of such pairs is provided with 105 110

independent means for effecting the operation or setting of its safety cams upon the breaking of the common sustaining cable. In order to eliminate one of such operating means and to thereby cheapen the cost of such elevators as well as render them simpler in construction, I coördinate the cam operating means of both elevator cars so that a single instrumentality becomes effective to set their safety cams. My preferred means to this end is illustrated in Fig. 6 of the drawings. The freight elevator cars 18 and 19, as shown therein, are suspended by a common cable 3^a which passes over sheaves 4^a supported by suitable frames (not shown). The safety cams and their operating means are, in this disclosure, the same as those illustrated in Figs. 1 to 5 and described above. In order to move the levers 9^a to their reverse positions, and thereby bring the cams 7^a into engagement with the guides 2^a when the sustaining cable 3^a breaks, I connect the levers 9^a of one elevator car to the corresponding levers 9^a of the other elevator car by means of ropes or cables 13^a and 13^b, passing over sheaves 14^a and 15^a at the top of the elevator shafts. The said ropes are preferably so adjusted as to sustain none of the weight of the elevator cars during the normal operation of the cars.

In case the sustaining cable 3^a breaks a double safeguard is, by this construction, provided against the falling of the elevator cars. The ropes may be of sufficient strength in themselves to sustain the elevator cars, but their primary function is to

set the safety cams in the manner described in connection with Figs. 1 to 5.

I claim as my invention:

1. In an elevator safety stop, the combination with an elevator car movable between guides, of a pair of rotary mounted shafts each provided with safety cams in positions to engage said guides, a sustaining cable, a pair of weighted cables, a pair of pivoted levers each connected at its inner end to said sustaining cable and at its outer end to one of said weighted cables, arms extending from said cam shafts and operatively engaged by said levers, and a pair of straps extending one over the inner end of each lever and connected to said car. 40

2. In an elevator safety stop, the combination with an elevator car movable between guides, of a pair of rotatably mounted shafts each provided with safety cams in position to engage said guides, and a sustaining cable for said car, a pair of weighted cables, a pair of pivoted levers, each lever being connected at its inner end to said sustaining cable and at its outer end to one of said weighted cables, said levers being slotted at their outer ends, arms extending from said cam shafts through the said lever 55 slots, and a pair of straps extending one over the inner end of each lever and connected to said car. 60

In testimony whereof I have hereunto set my hand.

JOHN HOFFER.
